MACHINE FOR RUPTURING THE ENDS PROJECTING FROM WIRE HEDDLES

Filed July 27, 1928

UNITED STATES PATENT OFFICE

AUGUSTE GILBERT DAVID AND PIERRE GISCLON, OF VILLEURBANNE, FRANCE

MACHINE FOR RUPTURING THE ENDS PROJECTING FROM WIRE HEDDLES

Application filed July 27, 1928, Serial No. 295,811, and in France July 28, 1927.

This invention relates to a machine for rupturing the ends of wire projecting from heddles made of wire and more particularly from twisted wire heddles.

5 According to the invention, the ends to be ruptured are given a number of successive flexions, by means of moving guides whereby rupture occurs just at the end of the twist.

The guides may be reciprocated or rotated; 10 they may be in the form of forks or bars.

The annexed drawing diagrammatically shows a machine according to this invention.

Fig. 1 is a plan view with broken parts.

Fig. 2 is a section on line II—II (Fig. 1).

15 Fig. 3 represents to an enlarged scale a heddle and the set of bars.

The machine comprises a table 1 supporting two triangular frames 2 on which rests the rotatable shaft 3.

20 Two depending arms 4 are keyed on shaft 3, and they support, at their lower ends, a bar 5. One arm 4 may be reciprocated by means of a connecting rod 6 which is actuated by a cranked shaft 7 driven by a motor 8 through a belt 9 and a pulley 10.

25 Two other arms 11 also depend from shaft 3 on which they are loose, and they support a second bar 12.

A cable 13 is attached to one arm 11; this 30 cable passes over idlers 14 and 15 and supports a counterweight 16 which thus tends to rock the arm 11 and to lift the bar 12.

35 A lever 17 is pivoted on each arm 4. Each lever 17 is provided with a groove 18 (Fig. 2) which may cooperate with a stud 19 fixed to the corresponding arm 11. When the two levers 17 are thus in engagement with the two studs 19, arms 11 and 4 are locked together.

Shaft 3 also loosely supports two levers 20 40 each one being provided at one end with a counterweight 21, whilst the other end is pivotally connected with a rod 22. The two rods 22 support a bar 23.

The frameworks 2 rotatably support a 45 shaft 24 provided with an actuating lever 25

and with two cams 26 which may cooperate with levers 20 in order to rock the same and thus press bar 23 against a bar 27 resting on table 1.

A bar 28 is placed between bars 5 and 12. 50 It is fixed by means of two stays 29 which are provided with notches 30 cooperating with studs 31 fixed on bars 5 and 12 and provided with fly-nuts or the like.

Table 1 also supports a bar 32 provided, at 55 its ends, with hooks 33 (Fig. 2).

The operation is as follows:

The parts being in the position shown, bar 28 is removed and levers 17 are lifted by hand; arms 11 and bar 12 are thus freed and 60 rocked by counterweights 16. Bar 12 contacts with rods 22 and drives the same. The parts thus assume the position shown in dot-and-dash lines, Fig. 2.

The heddles 34 are preferably maintained 65 by means of two rods or shafts 35 which are passed through their end rings (Fig. 3). They are disposed as shown in the drawings, one of rods 35 being engaged into hooks 33 the other one being free and supported only 70 by the heddles themselves, and the projecting ends 36 to be ruptured being in the neighbourhood of bar 5.

Arms 11 are then lowered and locked by 75 means of levers 17 (position represented in full lines). Rods 22 thus re-assume their vertical position.

Lever 25 is lowered and bar 23 is thus 80 pressed against bar 27, the heddles 34 being firmly maintained between the said bars.

Bar 28 is then placed between bars 5 and 12. As clearly shown, Fig. 3, the arrangement is such that the ends 36 to be ruptured are located between bars 12 and 28 or between bars 28 and 5.

The motor 8 is started and it reciprocates the three bars 5, 12 and 28 as a whole. The ends 36 are thus submitted to a number of successive flexions which rapidly cause their rupture exactly at the end of the twist.

It may be found useful, in order to avoid lateral bending of the ends 36, to provide a number of guides in the form of teeth 37, fixed to bar 12.

The machine may be combined with a machine for the manufacture of twisted wire heddles, the ends being thus ruptured without having to arrange the heddle on a special machine as described.

10 Of course, the bars 5, 12 and 28 could be fixed and the heddles reciprocated.

I claim:

1. A machine for rupturing the ends of wire projecting from wire heddles, comprising means for maintaining the heddles; guides receiving the ends to be ruptured; and means for moving said guides whereby said ends are given a number of successive flexions causing their rupture.

20 2. A machine for rupturing the ends of wire projecting from wire heddles, comprising means for maintaining the heddles; guides receiving the ends to be ruptured; said ends being loose in said guides; and means 25 for moving said guides, whereby said ends are given a number of successive flexions causing their rupture.

3. A machine for rupturing the ends of wire projecting from wire heddles, comprising means for maintaining the heddles; guides receiving the ends to be ruptured; and means for imparting to said guides a reciprocating motion, whereby said ends are given a number of successive flexions causing 35 their rupture.

4. A machine for rupturing the ends of wire projecting from wire heddles, comprising means for maintaining the heddles; guides receiving the ends to be ruptured; said ends being loose in said guides; and means 40 for imparting to said guides a reciprocating motion, whereby said ends are given a number of successive flexions causing their rupture.

45 5. A machine for rupturing the ends of wire projecting from wire heddles, comprising means for maintaining a number of heddles parallel to each other; substantially parallel bars in spaced relation, the ends to be ruptured being disposed in the space between said bars; and means for imparting to said bars as a whole, a reciprocating motion, whereby said ends are given a number of successive flexions causing their rupture.

55 6. A machine for rupturing the ends of wire projecting from wire heddles, comprising means for maintaining a number of heddles parallel to each other; three substantially parallel bars in spaced relation, the ends to be ruptured being disposed in the spaces between two bars; means for locking said bars together; and means for imparting to said bars a reciprocating motion, whereby said ends are given a number of successive flexions 60 causing their rupture.

7. A machine for rupturing the ends of wire projecting from wire heddles comprising a rotatable shaft; a number of arms depending from said shaft; a first bar fixed at the lower ends of some of said arms; a second bar fixed at the lower ends of the other of said arms, parallel to said first bar; means for locking said first-bar supporting arms with said second-bar supporting arms; a third bar removably fixed between said first bar and second bar in parallel and spaced relation thereto; means for maintaining a number of heddles parallel to each other, the ends to be ruptured being disposed in the spaces between said first, second and third bars; and means for reciprocating said first-bar supporting arms, whereby said ends are given a number of successive flexions causing their rupture.

8. A machine for rupturing the ends of wire projecting from wire heddles, comprising means for maintaining a number of heddles parallel to each other; substantially parallel bars in spaced relation, the ends to be ruptured being disposed in the spaces between said bars; teeth on said bars for laterally guiding said ends; and means for imparting to said bars as a whole a reciprocating motion, whereby said ends are given a number of successive flexions causing their rupture.

9. A machine for rupturing the ends of wire projecting from wire heddles, comprising a fixed bar on which the heddles are disposed; a vertically movable bar for pressing said heddles; vertical rods from which said movable bar depends; means for actuating said rods; substantially parallel bars in spaced relation, the ends to be ruptured being disposed in the spaces between said spaced bars; and means for imparting to said spaced bars as a whole a reciprocating motion, whereby said ends are given a number of successive flexions causing their rupture.

10. A machine for rupturing the ends of wire projecting from wire heddles, comprising a fixed bar on which the heddles are disposed; a heddle-pressing movable bar adapted to press said heddles on said fixed bar; vertical rods from which said heddle-pressing movable bar depends; means for actuating said rods; a shaft; arms depending from the same; a first working bar at the lower ends of some on said arms; a

110 second working bar at the lower ends of the other of said arms, parallel to said first working bar; a third working bar removably fixed to said first and second working bars, between the same and in parallel and spaced relation thereto; means for locking said first working bar with said second working bar; means together; and means for imparting to said bars a reciprocating motion, whereby said second working bar is caused to lift said second working bar when unlocked from said first working bar; means whereby said second working bar, when lifted, drives said heddle-pressing movable bar
